UNITED STATES PATENT OFFICE.

EUGENE BROWN, OF PEORIA, ILLINOIS.

DESIGN FOR A TOY.

SPECIFICATION forming part of Design No. 32,460, dated April 3, 1900.

Application filed February 23, 1900. Serial No. 6,313. Term of patent 3½ years.

To all whom it may concern:

Be it known that I, EUGENE BROWN, a citizen of the United States, residing at Peoria, in the county of Peoria and State of Illinois, 5 have invented and produced a new and original Design for Toys, of which the following is a specification, reference being had to the accompanying illustration.

As shown in the figure, the leading or material feature of my design consists in the representation of a bug A, suspended from the frame B. The frame B has lateral extensions a a, from opposite sides, to which are attached bands or straps C C, which in turn are attached

to opposite ends of the bug and by which the same is suspended from the frame B.

Having described my invention, what I claim as new, and desire to secure by Letters Patent of the United States, is—

The design for a toy, as herein shown and described.

In testimony whereof I have signed my name to this specification in the presence of two subscribing witnesses.

EUGENE BROWN.
